UNITED STATES PATENT OFFICE.

JESSE C. JOHNSON, OF SAN FRANCISCO, CALIFORNIA.

PRESSURE-CONTROL VALVE.

Application filed April 17, 1922. Serial No. 554,161.

To all whom it may concern:

Be it known that I, JESSE C. JOHNSON, a citizen of the United States, residing at 1337 Mission Street, San Francisco, in the 5 county of San Francisco and State of California, have invented certain new and useful Improvements in a Pressure-Control Valve, of which the following is a specification.

10 This invention relates to an automatic oil pressure control valve for rotary burners, and especially to means for automatically varying the oil flow to the burner as the fires are increased or decreased.

15 One of the objects of the present invention is to provide a simple, substantial and easily installed regulator, which is actuated by variations of the oil under pressure delivered to the burner.

20 Another object of this invention is to provide means actuated by the steam pressure of the boiler for automatically varying the oil under pressure delivered to the burner.

With these general objects in view and 25 others that will appear as the nature of the invention is better understood, the same consists in the novel combination and arrangements of parts hereinafter fully described, illustrated in the accompanying drawings 30 and then claimed.

In the drawings forming part of this application and in which like designating characters refer to corresponding parts throughout the several views:

35 Figure 1 is a front view of a boiler and furnace showing the application of the device; and

Fig. 2 is an enlarged sectional view of the pressure control valve.

40 Referring to the drawings in detail, indicating in general a boiler by 3 and the furnace front by 4. Suitably supported with relation to the said furnace front is an oil burner 5, the type of burner employed in 45 the present invention being such as shown in my Letters Patent entitled "Oil burner construction" issued October 17, 1916, No. 1,201,999.

I will not herein in detail describe or 50 claim the new burner element of my combination inasmuch the same per se, constitutes the subject of a co-pending application filed March 23, 1922, Serial No. 545,989.

A burner of this character consists of a 55 motor driven atomizer. The oil employed for combustion is delivered to the pumping

system 6, by means of a pipe 7. A pipe 8 connected with the pumping system carries a pressure actuated control valve generally indicated as at A. A pipe otherwise connected to the said pipe 8, not here shown, delivers a predetermined quantity of oil to the rotary atomizer by means of the constant pressure maintained by the said pumping system within the said pipe 8.

This control valve A is connected with a pressure regulator 9, of suitable construction, on the steam dome of the boiler, by means of a link 10, and it serves the function of varying the oil pressure in the pipe 8 between the valve A and the atomizer of the burner proper.

This pressure control valve remains at normal as long as the steam pressure in the boiler proper is below a predetermined point. The valve will, however, automatically open the moment a predetermined pressure prevails within the steam dome of the boiler, and acting in unison with the valve A, will open the same by release of the valve stem sleeve, allowing of more oil to return to the source of supply, thus lowering the oil pressure within the pipe 8, and reducing the quantity of oil delivered to the burner.

The pressure control valve is constructed substantially as shown in Fig. 2. It consists of a valve casing 11, having suitable couplings 12 and 13, a bonnet 14 is threaded into the upper end of the said valve casing as at 15. A cylinder 16 is formed within the valve casing and integral therewith, the said cylinder casing part being flared on its upper edge as at 16^a for reasons presently explained. A piston valve 16^b, comprising a piston 16^c, having a frusto-conical upper part 16^d and having a stem 17, is adapted to seat into and close the said cylinder casing part. Surrounding the stem is a coil spring 18. This coil spring is interposed between the flange 19, integral with the said stem and a sliding collar 20. Slidably mounted upon the valve stem 17 is a sleeve 21. This sleeve, surrounded by a packing gland 22, is slidably mounted into the upper end of the bonnet and extending exterior thereof, adjustment is had by a set nut 23. An annular flange 24, integral with the said sleeve, positioned at its lower end, is provided to limit the upward movement of the sleeve.

Arranged and seated below the adjustment nut 23, is a bearing bracket 25, secured

to this part of the bonnet by means of a collar 26, integral with the said bracket and having a set screw 27 for adjustment. Pivotaly mounted in the bearing bracket as 5 at 28, is a lever 29, having its short arm 30 operatively seating upon the upper end of the sleeve 21. An adjustment bolt 31, preferably threaded into the said bracket as at 32, having a set nut 33, is provided to limit 10 the movement of the lever arm 30.

The valve casing is divided into two chambers 34 and 35. The oil from the pumping system by means of pipe 8 enters the chamber 34 and it passes by the piston 15 valve 16^b before it enters the chamber 35 and returns to the source of supply. A constant quantity of fluid oil under pressure is maintained by the pumping system within the pipe 8 connected to the control valve by 20 coupling 12. Under normal conditions the oil within the pipe 8, on reaching a predetermined pressure will force the piston valve 16^b upwardly, thus allowing for an excess of oil supplied to return through the chamber 25 35 to the source of supply by means of pipe 8.

Mounted on the steam dome of the boiler is a suitable steam pressure regulator 9 having a bearing bracket 36 and a lever 37 30 pivotally mounted therein. A link 10 forms a connection between the lever 37 and the lever 29, as at 29^a, of the control valve. The steam within the boiler, on reaching a predetermined pressure will lower the lever 35 37, this is in turn transmitted through the link 10 to the lever 29 and to the valve stem sleeve 21. Release of the valve sleeve 21 by the lever arm causes the same to move upward, thus decreasing the tension of the coil 40 spring on the valve stem, thus released, the piston valve 16^b will more readily respond to the pressure of the fluid oil within the pipe 8 allowing of more of the oil to return to the source of supply. Lowering of the 45 oil pressure within the pipe 8 will reduce the supply of oil to the burner thus also lowering the fires underneath the boiler.

From the foregoing description it may be seen that I have provided means actuated 50 by the steam pressure of the boiler for varying the amount of oil delivered to the burner.

What I claim as new and desire to secure by Letters Patent is:

1. A control valve having a casing and a 55 chamber therefor, a piston valve, a stem for the said valve having an annular flange integral therewith, a collar slidably mounted on the said stem, a coiled spring secured between the said flange and the said collar, 60 normally urging the said valve stem downward to maintain the valve in its normal closed position, a sleeve slidably mounted on the said valve stem extending exterior of

the said casing, of a bearing bracket carried by the said casing, a lever pivotally mounted 65 in the said bracket adapted to urge the said sleeve downward upon the said valve stem.

2. In a fluid pressure system, the combination with a boiler, a source of pressure, a control valve having a casing and a chamber therefor, said chamber being open to the said source, of a piston valve, a stem for the said valve having an annular flange integral therewith, a collar slidably mounted on the said stem, a coiled spring interposed between 70 the said flange and the said collar, normally urging the valve stem downward to maintain the valve in its normal closed position against the said pressure source, a sleeve slidably mounted on the said valve stem extending exterior of the said casing, of a bearing bracket carried by the said casing, a lever pivotally mounted into the said bracket adapted to actuate upon the said sleeve, a regulator carried by the boiler having a 75 lever, means of connecting the said levers, said regulator adapted to open when the steam pressure within the boiler exceeds a predetermined point coacting in unison with the said control valve. 80

3. The combination with a boiler and furnace, of an oil burner for the furnace, a source of pressure, a pipe for delivering oil under pressure to the burner, a control valve on said pipe having a casing and forming a chamber therefor, said chamber being open to said source of pressure, a piston valve having a frusto-conical upper part, a stem for the said valve, having an annular flange integral therewith, a collar slidably mounted on said stem, a coiled spring interposed between the said flange and the said collar, normally urging the valve stem downwardly to maintain the valve in its normally closed position against the said pressure source, a sleeve slidably mounted on the said valve stem extending exterior of the said casing and having an annular flange positioned on its lower end, of a bearing bracket carried by the said casing, a lever pivotally mounted into the said bracket adapted to actuate upon the said sleeve, means for adjusting the movement of said lever carried by said bearing bracket, a regulator carried by the boiler and having a lever, means of connecting the said levers, said regulator adapted to open when the steam pressure within the boiler exceeds a predetermined point and cooperating with the said control valve. 100

In testimony whereof I have affixed my signature in the presence of two witnesses.

JESSE C. JOHNSON.
